HENRY T. MOODY, OF NEWBURYPORT, MASSACHUSETTS.

Letters Patent No. 87,582, dated March 9, 1869.

IMPROVED CAR-COUPING.

The Schedule referred to in these Letters Patent and making part of the same.

To all whom it may concern:

Be it known that I, HENRY T. MOODY, of Newburyport, in the county of Essex, and State of Massachusetts, have invented certain Improvements in Car-Couplings; and do hereby declare the following to be a full, clear, and exact description thereof, reference being had to the accompanying drawings, in which—

Figure 1 is a transverse sectional view of my invention.

Figure 2 is a plan view.

(Both these figures show the coupling as shackled.)
Figure 3 is a view of the link detached from the coupling.

The object of my invention is to produce a car-coupling, which will enable two cars to be shackled without attention, that is, in a measure, act automatically, and which shall be simple in construction, strong and inexpensive, and which will allow of using the ordinary link, if it is desired, without change or modification; also to give a coupling which will operate without the use of springs in any form, as springs, no matter how they may be adjusted, in a car-coupling where great strength is needed, are always objectionable, for many obvious reasons, such as liability of loss of elasticity, of breaking, &c.

The nature of my invention consists in the use of draw-heads, flaring at their mouth, one with a weighted tongue, for holding the shackle-pin, the other, holding the shackle-link, the link being kept in nearly a horizontal position, by its length projecting into a chamber within the draw-head, and prevented from too much side motion by a rubber bearing.

In the drawings—

A represents a coupling-box, or draw-head, having chamber B, which may be more or less extended. The mouth of the box flares at a b. This box A is used on one car.

A' is a coupling-box, or draw-head, for use on the car opposite the one using draw-head A.

A' has recess or chamber B'.

D and D' are pins for shackling.

E is a link, of form shown, having elongation E' and hole d, for the reception of pin D.

n is a shoulder on the lower side of the link E, and surrounding hole d.

F is a shoulder, coming up from the lower side of A.

The object of shoulder F and n is to assist in preserving a horizontal position to the link E, when the coupling is unshackled.

R is a rubber bearing, placed upon E, when it extends into inner recess B.

The object of rubber R is to prevent too much lat-

eral motion of the link, and assisting to preserve a straight horizontal position of link E, that it may the more readily find, in shackling cars, the mouth of the coupling-box of the opposite car.

H is a tongue or arm, curved in form, from rear of the recess B' toward the front and upper side a.

This arm H has a weight at I.

The arm is hung, at p, upon a pin running from side to side of the case of the draw-head.

When the shackling-pin D' is withdrawn, as shown by the red lines D'', the arm H, by the force of weight I, falls forward, and with its forward point covers the hole m, in the position shown by red line H'. Thus the pin D' may rest upon arm H. Now, when the link E, when two cars are coming together, finds the mouth a' b' of coupling-box or draw-head A', and strikes the front of the curve of arm H, at once pushing it back, withdrawing the same from under the pin D', and allowing the pin D' to fall to its position through the link E, the cars are firmly shackled.

If it is desired, the ordinary link may be used, instead of the one I have shown. This would only be necessary while cars were undergoing a change of couplings, and some were provided with my improved coupling, and others were not; or in case the cars of one line, provided with this coupling, were in temporary use upon another line, it can easily be used without modification.

The operation, then, of my invention is simple, and as follows:

The pin D' being left up, and held by arm H, the link of the approaching car finds the mouth of the draw-head, and, pushing back H, lets D' fall to its place, thus automatically shackling the cars, and overcoming the many objections to the ordinary methods.

Having thus fully described my invention,

What I claim as new, and desire to secure by Letters Patent, is—

The combination of link E and tongue or arm H, (when acting auxiliary to each other,) with the draw-head A, having chamber B and shoulder F, draw-head A', and shackle-pins D and D', all constructed and operating relatively to each other, substantially as described and specified.

In testimony whereof, I have signed my name to this specification, in the presence of two subscribing witnesses.

HENRY T. MOODY.
